Primary Examiner—Bernard Ansher*Assistant Examiner*—Philip Hyder*Attorney, Agent, or Firm*—Dorsey & Whitney**[57] CLAIM**

The ornamental design for a stair climber exercise machine, as shown.

DESCRIPTION

FIG. 1 is a perspective view of the stair climber exercise machine showing our new design;

FIG. 2 is a right side elevational view thereof, the left side elevational view being a mirror image thereof;

FIG. 3 is a top plan view thereof;

FIG. 4 is a bottom plan view thereof;

FIG. 5 is a front elevational view thereof; and,

FIG. 6 is a rear elevational view thereof.

*Fig. 1**Fig. 2**Fig. 3**Fig. 4****Fig. 5******Fig. 6***
